KEYLESS LOCK

Harry A. Barrett, Upper Darby, Pa., assignor to
 Barrett Automatic Keyless Lock Co., a corpora-
 tion of Delaware

Application November 1, 1932, Serial No. 640,587

18 Claims. (Cl. 70—25)

This invention relates to fastening devices, known generically as locks, and more particularly to portable types, as padlocks of permutative character in which no key is required.

5 It is an object of the present invention to provide a compact lock of this type, which, by reason of its construction, effectually resists all attempts at so called picking or surreptitious attempts at opening, short of actual destruction.

10 A further feature is in the provision of a keyless lock in which the operative elements are mechanically actuated by positive means, no springs or resilient parts being employed.

Another purpose is to produce a lock of exceptional strength, economically manufactured and not readily liable to disorganization.

These and other advantageous objects are accomplished by the novel construction, combination and arrangement of parts as hereinafter described and shown in the accompanying drawing, forming a material part of this disclosure, and in which:

Fig. 1 is a side elevational view of an embodiment of the invention, shown in closed position.

25 Fig. 2 is a similar view of the same, the actuating knob and dial being omitted, showing the parts in full lines as in locked position and the dash-dot lines showing the open position of the parts.

30 Fig. 3 is a transverse sectional view taken on line 3—3 of Fig. 2.

Fig. 4 is a plan view showing a modified form of the lock as applied to a container.

The structure embodies a casing 10 having a circular wall and integral flat side 11, opposite which the narrow wall is recessed to receive a bezel 12 held permanently in position by spinning the thin material over it, as at 13.

The bezel 12 retains in rotative engagement, 40 over the open side of the casing, the flanged peripheral edge of a dial 14 provided with an integral twirling knob 15, and bearing on its exposed face, a series of gradations readable with respect to an index point on the casing.

45 Integrally formed on the cylindrical surface of the casing 10, at a spaced distance apart, are lugs 17 and 18 extending to a uniform height. On the inner side of the casing, in register with the lug 18, is a corresponding lug 19, these lugs all being bored to receive the legs or parallel bar elements 20—21 of a curved shackle or locking member 22.

This shackle is of circular cross section, the shorter leg 20 containing in its inner edge a recess 23 adjacent its extremity, while in the opposite leg 21 is a recess 24, this longer leg extending

normally through the lugs 18—19 and being provided with a stop ring 25.

Engageable in the recess 23 is a bolt 26, formed on an arm of a bell-crank lever 27 held by a shoudered pivot screw 28 to the wall 11 of the casing 15 but spaced therefrom, as shown in Fig. 3.

Another arm of the bell-crank lever 27 is provided with an upstanding lug 29 to be contacted by the bottom of the leg 20 when the shackle is in its lowermost position, thereby locking the bolt 26 in a holding position within the recess 23.

Another arm of the bell-crank lever is provided with an upstanding detent 30, the purpose of which will later appear.

A fourth arm 31, of the bell-crank lever 27, has pivoted at its extremity an angular deflector 32, provided with a finger 33; the deflector 32 being adapted to operate in a pocket 34 formed in the casing by a lug 35 having an angular upper edge.

A plain straight lever 37, having a depending lug 38, is mounted on a pivot 39 at a point nearly opposite the pivot 28. One end of the lever 37 is adapted to enter the recess 24 in the longer leg 21 of the shackle when the same is in a closed position, and is moved into the recess 24 by reason of the opposite end of the lever contacting with the detent 30 of the bell-crank lever 27 when raised, thus locking both legs of the shackle simultaneously.

A post 40 extends inwardly from the lower wall 11 of the casing centrally thereof, the post having a hub 41 on its lower end while its upper end reaches into an axial recess 42 in the knob 15.

Revolutely mounted on the post 40, to rest upon the hub 41, is a tumbler disc 44 above which are other similar discs 45 and 46; a down reaching pin 47 being fixed in the lower side of the disc 44 and an upstanding pin 48 in its upper side, as seen in Fig. 2. A pin 49 extends upwardly from the uppermost disc 46 to engage in a recess in the knob 15 and the intermediate disc 45 is provided with pins to translate movement from the disc 46 to the disc 44.

These discs are also provided, at a point in their periphery, midway, with narrow radial slots 50 engageable by the detent 30 of the bell-crank lever, these slots being arranged with reference to the pins, which are adapted to rotate within the confines of spacer arms 52 disposed intermediate the discs, these spacers being anchored by extensions 53 set in an undercut slot 54 formed in a thickened portion of the casing wall opposite the shackle.

By referring to Figure 2, it will be noted that 55

when the shackle elements are pressed inwardly of the casing, the end of the leg 20 will contact the lug 29, turning the bell-crank lever releasing the detent 30 from the slots 50 of the several discs 44—45—46 and at the same time causes the lever 31 to enter the recess 24 in the longer leg 21 of the shackle, and furthermore, due to the shape of the deflector 32 causes its finger 33 to contact the pin 47 of the lowermost disc, thereby moving the slots out of the path of movement of the detent 30, locking the device.

It will also be noticed that when the device is opened—that is when the shackle 22 is withdrawn, the lower part of the leg 21 prevents the lever 31 from being turned on its pivot and thus prevents the detent 30 from being withdrawn from slots 50 until the shackle is slid "home". This likewise prevents the knob 15 from being turned "off combination" while the device is open.

20 In the modification shown in Fig. 4, the body of a container 60, such as a desk, chest or trunk, is provided with a cover 61 in which are secured opposed bolts 62 having recesses 63 of a nature similar to the recesses 23—24 of the shackle 22.

25 These elements are adapted to enter corresponding openings in the wall of the container, to engage in projecting lugs 17', 18' of a lock of the type described, composed of a casing 10', dial 14' and knob 15', all the interior elements 30 being of the same type as previously described.

Although the improvements have been described with considerable detail and with respect to certain particular forms of the invention, it is not desired to be limited to such details since 35 many changes and modifications may well be made without departing from the spirit and scope of the invention in its broadest aspect.

Having thus described the invention, what is claimed as new and desired to secure by Letters 40 Patent, is:

1. A lock mechanism associated with a casing and comprising a shackle having parallel leg elements of unequal length enterable in said casing, both leg elements having notches in their inner surfaces, means on the longer of said legs to prevent extraction, a lever pivoted in said casing to be oscillated by contact with the shorter of said legs when fully entered, a bolt on said lever to engage in the notch of the shorter leg, a second lever pivoted in said casing engageable in the 45 notch of the longer leg, and means on said first lever to cause said engagement of the second lever simultaneously with engagement of said bolt.

2. A springless lock mechanism associated with a casing and comprising a shackle having leg elements of unequal length enterable in said casing, both leg elements having notches in their inner surfaces, means on one of said legs to prevent extraction, a lever pivoted in said casing to be oscillated by contact with the shorter of said legs when fully entered, a bolt integral with said lever to engage in the notch of the shorter leg, a second lever pivoted in said casing engageable in the notch of the longer leg, and manually 60 operable, permutative means to control movement of said first lever.

3. A springless lock mechanism associated with a casing and comprising a shackle having parallel legs of unequal length enterable in said casing, each leg containing a single notch in its inner surface, means on the longer of said legs to prevent extraction, a lever pivoted in said casing to be oscillated by contact with the shorter of said legs when fully entered, a bolt on said 70

lever to engage in the notch of the shorter leg, a second lever pivoted in said casing engageable in the notch of the longer leg, means on said first lever to cause engagement of the second lever simultaneously with engagement of said bolt, a series of permutative discs having registerable slots, a detent on the first lever enterable in the slots when aligned and normally resting on their peripheries, means for manually causing registration of the disc slots, and means carried by 10 the first lever to automatically rotate at least one of the discs, upon action of the lever in one direction.

4. A springless lock mechanism associated with a circular casing having a pair of outstanding lugs, and comprising a shackle provided with legs 15 slidable in bored openings in said lugs, one of said legs being longer than the other and adapted to rotate in its opening, and each leg containing a single notch in its inner surface means to prevent complete withdrawal of said shackle from said casing, a lever pivoted in said casing, said lever having an arm extending into the path of the shorter leg, a bolt on said lever to engage in the shorter leg notch, a detent on 25 said lever, a series of apertured discs revolvable axially in said casing, said discs being interengaged to operate in sequence, manual means to rotate said discs into known relation thereby to receive said detent, and means pivoted on said lever to move said discs out of registration when said bolt is engaged in the notch of the shorter leg.

5. A springless lock mechanism associated with a casing and comprising a shackle enterable in 35 said casing, a lever pivoted in said casing to be oscillated by contact with a leg of the shackle when fully entered, a bolt integral with said lever to lock the shackle against withdrawal when 40 fully entered, a series of permutative discs having registerable slots, a detent integral with said lever enterable in the slots when aligned, but normally resting adjacent their peripheries, means for manually causing registration of the disc slots and positively actuated means carried by 45 the lever to automatically rotate at least one of the discs upon rocking of the lever in one direction.

6. A springless lock mechanism associated with a casing and comprising a shackle enterable in 50 said casing, a lever pivoted in said casing to be oscillated by contact with a leg of the shackle when fully entered, a bolt integral with said lever to lock the shackle against withdrawal when 55 fully entered, a series of permutative discs having registerable slots, a detent integral with said lever enterable in said slots when aligned, but normally resting adjacent their peripheries, means for manually causing registration of the disc slots and a positively actuated pivoted element carried by the lever to automatically rotate 60 at least one of the discs, upon rocking of the lever in one direction.

7. In a combination padlock having a locking bolt lever and a series of tumblers for controlling 65 the actuation of the lever, the combination with the tumblers of a mechanism actuated solely by positive motion comprising a tumbler deflector and means to operate said deflector so that at least one of the tumblers will be automatically 70 moved upon rocking of the lever in one direction.

8. In a combination padlock having a locking bolt lever and a series of tumblers for controlling 75 the actuation of the lever, the combination with the tumblers of means actuated solely by positive

motion, carried by the locking bolt lever, and means cooperating therewith to effect automatic rotation of at least one of the tumblers upon rocking of the lever in one direction.

5. 9. In a combination padlock having a locking bolt lever and a series of tumblers for controlling the actuation of the lever, the combination with the tumblers of a member freely pivoted to said lever, to be positively rotated about its pivot, 10 when the lever is rocked in one direction, to rotate at least one of the tumblers.

10. In a lock, the combination of a lock case, a shackle mounted to slide in the lock case, a shackle retainer for limiting the outward movement 15 of the shackle, tumbler mechanism provided with a plurality of gatings adapted to register with each other, a bolt pivotally mounted in the casing adapted to engage the toe of the shackle when the shackle is moved into the lock case, and to lock said shackle in the casing when said tumbler gatings are out of register; said bolt, when said tumbler gatings are in register, being permitted to turn to release the toe of the shackle; and a device in operative engagement 20 with said bolt to move into locking engagement with the heel portion of the shackle when said bolt is moved into locking engagement with the toe of the shackle.

11. In a lock, the combination of a lock case, a shackle mounted to slide in the lock case, a locking bolt assembly adapted, when the shackle toe is moved into the lock case, to be actuated by the shackle to position said locking bolt assembly in locking engagement with both the toe and heel 25 of the shackle; and tumbler mechanism for retaining the bolt assembly in said locking engagement with the toe and heel of the shackle, and adapted to be positioned to permit release of said bolt assembly from locking engagement with the 30 shackle.

12. In a lock, the combination of a lock case, a shackle mounted to slide in the lock case, a bolt pivotally mounted in the lock case and adapted to be engaged by the shackle when the shackle is moved into the lock case so as to be moved thereby into locking engagement with the toe of the shackle, a pawl actuated by the movement of said bolt in a manner to be moved thereby into locking engagement with the heel of the shackle, and 40 tumbler mechanism for retaining the bolt and pawl in said locking engagement with the shackle and adapted to be positioned to effect release of said bolt and pawl.

13. In a lock, the combination of a lock case, a shackle mounted to slide in the lock-case, a bolt pivotally mounted in the lock case and adapted to interlock with the toe of the shackle when the shackle is moved into the lock-case, a pawl in engagement with the bolt so as to be moved thereby to interlock with the heel of the shackle when the bolt moves to interlock with the shackle toe, and means for retaining the bolt and pawl in locking engagement with the shackle, said means being adapted to be actuated to release 50 said bolt and pawl.

14. In a lock, the combination of a lock-case, a shackle mounted to slide in the lock-case, a bolt pivotally mounted in the lock case and adapted to

interlock with the toe of the shackle when the shackle is moved into the lock-case, and means interposed between the bolt and the heel of the shackle for preventing the bolt from moving into its locking position when the shackle is withdrawn from the lock-case. 5

15. In combination, a lock-case, a shackle, a bolt adapted to be moved into locking engagement with the shackle when the shackle is moved into the lock-case, tumbler mechanism having a plurality of gatings which when the gatings are in alinement hold the bolt in locking engagement with the shackle, a pawl in pivotal connection with said bolt, means operable to move said pawl with relation to said bolt and to translate said pawl, when said bolt is in motion, operably to cause said pawl to actuate said tumbler mechanism to move the gatings out of register. 15

16. In a lock mechanism, the combination of a lock-housing, a locking member mounted to move 20 with respect to said housing, a bolt adapted to be engaged by said locking member in a manner to move into locking engagement therewith, when said locking member is moved in one direction; tumbler mechanism which when in one position 25 permits the bolt to be moved to release said locking member, and when the mechanism is out of said position holds the bolt in locking engagement with said locking member; means to retain said tumbler mechanism in said release position when 30 said locking member is moved in another direction, and means cooperating with means carried by said bolt for moving said tumbler mechanism to said position in which the bolt is held in locking engagement with said locking member. 35

17. In a lock, the combination of a lock housing, a shackle mounted to move with respect to the lock-housing, a bolt adapted to be moved into locking engagement with the shackle when the shackle is moved in one direction, tumbler mechanism which when in one position permits the bolt to be moved to release the shackle and when the mechanism is out of said position holds the bolt in locking engagement with the shackle, a pawl carried by said bolt and adapted, when said bolt is moved, to actuate movement of said tumbler mechanism, operably to move said mechanism to said position in which the bolt is held 40 in locking engagement with the shackle. 45

18. In a lock, the combination of a locking member adapted to move in a plurality of directions; a bolt adapted to be engaged by said locking member in a manner to move into locking engagement therewith when said locking member is moved in one direction; tumbler mechanism 50 which when in one position permits the bolt to be moved to release said locking member, and when the mechanism is out of said position holds the bolt in locking engagement with said locking member, means to retain said tumbler mechanism 55 in said release position when said locking member is moved in another direction, and a pawl deriving motion from the motion of said locking member and adapted to move said tumbler mechanism to said position in which the bolt is held 60 in locking engagement with said locking member. 65

HARRY A. BARRETT.
